(57) **CLAIM**

The ornamental design for a bone spacer mold system, as shown and described.

DESCRIPTION

FIG. 1 is a perspective view of a bone spacer mold system showing my new design;

FIG. 2 is a bottom perspective view thereof;

FIG. 3 is a front elevational view thereof;

FIG. 4 is a right-side elevational view thereof;

FIG. 5 is a left-side elevational view thereof;

FIG. 6 is a top plan view thereof; and,

FIG. 7 is a bottom plan view thereof.

The broken lines showing certain features of the bone spacer mold system in FIG. 1-7 are included for the purpose of showing environmental structure and form no part of the claimed design.
